UNITED STATES PATENT OFFICE.

WILLIAM HERSCHEL COLLINS, OF BUFFALO, NEW YORK.

DESIGN FOR A BAKE-PAN.

SPECIFICATION forming part of Design No. 34,668, dated June 18, 1901.

Application filed March 29, 1901. Serial No. 53,563. Term of patent 7 years.

To all whom it may concern:

Be it known that I, WILLIAM HERSCHEL COLLINS, a citizen of the United States, residing at Buffalo, in the county of Erie and State of New York, have invented and produced a new and original Design for Bake-Pans, of which the following is a specification, reference being had to the accompanying drawing, forming a part thereof.

This design relates to the shape or configuration of bake-pans.

The accompanying drawing is a perspective view of a bake-pan embodying my design.

As shown in the accompanying drawing, the leading feature of my design consists of a substantially rectangular-shaped baking-pan having beveled corners, the walls of the pan tapering outwardly from the bottom thereof.

The beveled portions or corner-panels A

constitute a part of the wall of the pan, and these panels are flat and of substantially equal width at all points throughout their lengths.

The wall of the pan is provided with a narrow overturned edge b.

Extending entirely around the base of the pan is a border-strip c.

The entire wall of the pan, both interiorly and exteriorly, is perfectly plain and unbroken.

What I claim is—

The design for a bake-pan, substantially as herein shown and described.

Witness my hand this 21st day of February, 1901.

WILLIAM HERSCHEL COLLINS.
